(57) **CLAIM**

The ornamental design for a display screen with icon group and display screen with icon set, as shown and described.

DESCRIPTION

FIG. 1 is a front view of a display screen with icon group showing our new design;

FIG. 2 is a front view of a display screen with icon set showing our new design; and,

FIG. 3 is a front view of a display screen with icon group shown on a device.

The broken line showing of the display screen, text, and graphic features forms no part of the claimed design.

1 Claim, 3 Drawing Sheets

FIG. 1

FIG. 2

FIG. 3
